CLAIM

I claim the ornamental design for an external solid state drive, as shown and described.

DESCRIPTION

FIG. 1 is a perspective view of an external solid state drive showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

The illustrative broken line showing of an ovular recess in FIGS. 1 and 5 is exemplary only and does not form part of the claimed design.
